UNITED STATES PATENT OFFICE.

RICHARD HAMMERLY, OF NEW YORK, N. Y.

FIRE-ESCAPE.

SPECIFICATION forming part of Letters Patent No. 705,580, dated July 29, 1902.

Application filed May 2, 1902. Serial No. 105,573. (No model.)

To all whom it may concern:

Be it known that I, RICHARD HAMMERLY, a citizen of the United States, and a resident of New York city, county and State of New York, have invented certain new and useful Improvements in Fire-Escapes, of which the following is a specification.

This invention relates to a fire-escape which can be readily manipulated and by which a safe and easy descent may be accomplished.

In the accompanying drawings, Figure 1 is a front view of my improved fire-escape; Fig. 2, a side view thereof; Fig. 3, a rear view; Fig. 4, a section on line 4-4, Fig. 3; and Fig. 5, a detail of the brake-shoe.

The letter *a* represents a frame or casing traversed from side to side by an open tube *b*. This tube is provided within the frame at its ends with oppositely-placed tapering shoulders or abutments *b'*, that guide the rope *A* in parallel coils around the tube, the maximum thickness of the abutment being equal, substantially, to the thickness of the rope. The rope *A* enters the casing *a* through an upper tubular guide *c*, is thence wound around the tube *b* between the abutments *b'*, and leaves the casing through a lower tubular guide *d*, arranged diametrically opposite the guide *c*.

The guide *c* contains a removable curved brake-shoe *e*, Fig. 5, which is provided with a laterally-projecting pin *e'*, that enters a perforation *c'* of the guide *c*. Above the perforation *c'* the guide *c* is provided with a second tapped perforation, which is engaged by a set-screw *f*, that impinges against the shoe. By manipulating this set-screw the shoe is forced against the rope to regulate the speed of the descent. The pin *e'* serves to hold the brake-shoe in position and permits its ready renewal when worn.

The lower guide *d* contains a brake-shoe *g*, similar in all respects to the shoe *e*, it being provided with a pin *g'*, entering perforation *d'* of guide *d* and being set by means of a screw *h*.

The rope *A* is suspended from the window to the ground, and the person descending is suspended from the frame *a* by means of a rope *B*, passing through the tube *b*. In lowering himself the person slackens the lower set-screw *h* and regulates his descent by the upper set-screw *f*, so that the frame will glide gradually down along the rope *A*. When the descent has been accomplished, the rope is pulled up and reversed and the screw *f* is slackened, when the apparatus is in condition for a second descent.

What I claim is—

1. A fire-escape composed of a frame, a transversely-extending tube, a weight-sustaining rope passing through the tube, a suspending-rope coiled around the tube, rope-guides at opposite ends of the frame, and brakes within said guides, substantially as specified.

2. A fire-escape composed of a frame, a transversely-extending tube, a weight-sustaining rope passing through the tube, a suspending-rope coiled around the tube, perforated tubular rope-guides at opposite ends of the frame, removable brake-shoes having laterally-extending pins engaging the rope-guide perforations, and set-screws engaging the shoes, substantially as specified. 75

Signed by me at New York city, New York, this 1st day of May, 1902.

RICHARD HAMMERLY.
